UNITED STATES PATENT OFFICE.

FRANCIS MARION VANDEGRIFT, OF WAUKEGAN, ILLINOIS.

FROST-PROOF WATER-TANK.

SPECIFICATION forming part of Letters Patent No. 789,077, dated May 2, 1905.

Application filed May 11, 1904. Serial No. 207,500.

To all whom it may concern:

Be it known that I, FRANCIS MARION VANDEGRIFT, a citizen of the United States, residing at Waukegan, in the county of Lake and State 5 of Illinois, have invented certain new and useful Improvements in Frost-Proof Water-Tanks and Protective Casings Therefor; and I do hereby declare the following to be a full, clear, and exact description of the invention, 10 such as will enable others skilled in the art to which it appertains to make and use the same.

My invention has for its principal object to provide a tank for water—such as used for railways, live stock, fire protection, and other 15 purposes—which shall be entirely independent of the inclosing shell or casing and the parts of which said tank is composed being made entirely of wood and assembled without the use of hoops, staves, nails, bolts, pins, 20 or analogous fastening means and which shall possess the great advantage over many devices of a like nature in use at the present time of being thoroughly frost-proof.

A further object is so to construct the 25 inclosing shell, box, or casing relative to the contained tank that it shall enhance the frost-proof quality of the tank.

With these objects in view the invention consists in the novel construction and combination of parts of a device characterized by 30 my invention, as will more fully hereinafter appear in the specification and as then particularly pointed out in the claims.

In the accompanying drawings, in which like 35 letters of reference indicate corresponding parts in the several views, Figure 1 is a perspective view of my improved device, the hinged cover thereof being thrown back to display the interior construction. Fig. 2 is a top 40 plan view, partly in section, of my improved device, the cover thereof being removed to display the interior construction. Fig. 3 is a sectional view through the device on line $a-a$, Fig. 2. Fig. 4 is a sectional view through 45 the device on line $b-b$, Fig. 2. Fig. 5 is a perspective view of the tank removed from the device. Fig. 6 is a detail view of one of the tightening-keys removed from the device. Fig. 7 is a detail view of one of the movable 50 tightening-keys removed from the device.

Fig. 8 is a detail collective view of a set of fastening-keys and a sill removed from the device, showing their manner of assemblage and operation. Fig. 8^a is a detail fragmentary view of a portion of the bottom of the 55 device, showing the opening therein and the lower ends of the fastening-keys projected therethrough. Fig. 9 is a detail view of a small wedge-key, and Fig. 10 is a detail reduced view in perspective of one of the sills 60 removed from the device.

Referring to the drawings in detail, the water-tank (designated generally by A and shown best in Fig. 5) of any preferred shape, as square or oblong, and of any desirable dimensions preferably comprises the bottom a and the four walls a' a'' a''' a'''' ; these parts being preferably formed of wood, desirably two-inch plank, grooved, dovetailed, or mortise-jointed in the usual and well-known manner 70 and, as shown in Fig. 5, to obviate the employment of hoops, staves, nails, pins, bolts, or like fastening means, the joints being preferably well leaded with white lead. The walls a' a'' of the tank are mortised, as at a^5 , in which mortises the walls a''' a'''' of the tank fit. What I designate as a "half" or "supplemental" cover A', desirably rigidly secured to the top of the tank in any suitable manner, 75 may be provided comprising the upper and lower portions a^6 a^7 , separated to form an air-space a^8 by pieces a^9 a^{10} . This auxiliary cover, as shown, covers approximately about half of the space formed by the four walls of the tank.

The casing or inclosing protective shell B, 80 desirably also of wood, preferably comprises the bottom b , having openings b' b'' b''' b'''' therein, Fig. 8^a, and the four walls b^2 b^2 b^3 b^3 , the walls b^2 b^2 having lower openings b^4 b^4 b^4 b^4 therein. Sills C C, having mortises c c c c , Fig. 10, near each end thereof, registering with the openings b^4 b^4 b^4 b^4 in the bottom of the casing, rest in the openings b^4 b^4 b^4 b^4 , the ends of said sills projecting beyond the casing and being protected from splitting, wearing away, or the like by strips of some suitable metal, as iron, tin, or the like c , the iron strips being secured to the sills by bolts c^2 of the required size.

Suitably secured to the sides of the sills 100

2
C C, midway of the depth thereof and bridging the space therebetween, is a supplemental or false bottom c^3 , forming an air-space between the bottom b and also an air-space between this false bottom c^3 and the bottom a of the tank, which bottom a rests on the supporting-sills C C, Fig. 3.

Preferably partitions $b^6 b^5 b^6 b^6$ between the four walls of the casing B and those of the tank A form air-spaces $b^7 b^7 b^7 b^7$.

Mounted in the openings $b^8 b^8 b^8 b^8$ in the top of the front and rear walls of the casing B and resting on the top of the walls of the tank are sills D D, which have, near their ends, mortises (similar to those lettered c , Fig. 10, in the lower sills) through which and through the mortises c in the lower sills C C and through the openings $b' b' b' b'$ in the bottom of the casing pass sets of vertically-arranged locking-keys (three to a set) holding the upper and lower sills and the tank against displacement or movement in the following manner: Through the mortises in each end of the several sills pass a set of these locking-keys, each set comprising three keys, two of which, E, are at both ends headed, as shown at e , so that when inserted vertically through the mortises in the sills and through the opening in the bottom of the casing these headed ends will hook on the tops of the upper sills D D, Fig. 1, and on the bottom of the lower sills C C, Fig. 8^a, thus holding the sills and the tank firmly in place against accidental displacement. The third or center key e' of each set is adapted to be driven between the other two keys of the set, one of which in operation rests against the forward end of the mortise in the sill, the other pressing against the side of the tank. (Shown in dotted lines in Fig. 4.) The mortises in the sills are cut, as shown, so that in case of shrinkage or the like of the tank it is only necessary to tap or strike the keys e' farther in, which will tightly bind the tank in position and eradicate any movement thereof. The keys e' thus act as wedges, and it will be seen that the upper and lower sills and the locking-keys passing therethrough coöperate to adjust the tank immovably in place.

50 The sills D D, similarly to the sills C C, have their ends projecting beyond the casing protected against splitting or wearing away by strips of iron, tin, or the like d^2 , the iron strips being secured to the sills by a bolt or 55 by bolts or the like d^3 , of required size.

Small tapering wedge-keys F F F F, held in place on top of walls $a' a^2$ of the tank and in grooves f in the under sides of the top sills D D by being rabbeted, as at f' , may be provided to act as wedges, thus additionally to insure the tank against the least vertical movement. As said, the small wedge-keys are held initially against displacement by being rabbeted, the rabbeted portion fitting snugly in 60 the groove of the sill; but in the event that

the tank becomes warped or contracted in height these small keys are driven farther in to take up any play caused by the contraction, and small keys F F F F may be provided, disposed, as shown in Fig. 4, on top of the two lower sills C C between the walls $a' a^2$ of the tank and the adjacent locking-keys E, thus insuring that the several pieces of which the bottom a of the tank is composed shall be drawn tightly together and also serving to bind the lower portions of the walls $a' a^2$ of the tank firmly against the walls $a' a^2$ thereof, as will be readily understood.

It is to be understood that, if desired, the water-tank may be painted interiorly and exteriorly.

It will be noted that the construction of the tank and the casing with interposed air-spaces will conduce to effective frost-proofness of the water-tank. Additionally to insure that the water-tank shall be thoroughly frost-proof I may suitably arrange over the walls thereof one, two, or more thicknesses of tar or felt paper according to the kind of paper used, and as this is an obvious expedient I have deemed it unnecessary to illustrate it.

Along two sides of the top of the casing are secured boards H H, each notched at $h h$ to admit of the headed ends of the fastening or locking keys E and e' being projected through said boards. The inner longitudinal sides of the boards press down on the upper sills D D, the boards being removably secured to the top of the casing-walls $b^3 b^3$, as by screws or the like.

The cover proper, I, for the tank and casing completely bridges the entire tank and comprises two substantially similar portions $i^2 i^2$, the portion i^2 being removably suitably secured along three sides thereof, as at i^3 , respectively, to the top of the wall a^2 of the casing and the two upper sides of the upper sills D D, as shown. The portion i' is hinged, as at $i^5 i^5$, to the portion i^2 , so that it may be swung back to afford access to the water in the tank, as desired. Said portion i' is provided on its under side near each end with a plurality of strips i^6 , bridged or connected by boards $i^7 i^8$, the rim or edges of the board i^8 when the cover I is closed tightly fitting and pressing against the top of the walls $a' a^3 a^4$ of the tank and the forward or front edge of the board i^7 resting against the top of the partition b^6 , thus forming an air-tight and frost-proof closure.

It will be observed from the description that the device as a whole is air-tight and by its construction thoroughly frost-proof, keeping the water in the tank cool in summer and warm in winter. It will also be observed that the tank is really entirely independent of the casing—i. e., is not secured or fastened thereto by nails or the like—thus admitting of its being tightened up or loosened or removed from the casing at will.

It will be understood that various minor modifications may be made in the details of construction of my device without departing from the spirit of my invention—as, for instance, in very large tanks, such as railway-tanks, it may be found desirable to have sills running at right angles to, from, and under the lower sills C C, such auxiliary sills to be fastened and keyed the same as the sills C C described—and that I do not confine myself in practice to the uses stated herein of my device, as it is obvious that it is applicable to any use where it may be employed advantageously—as, for instance, the device of my invention may be used as an ice box or chest and in such use will be found very efficacious in preserving the life of the ice.

Having thus fully described my invention, what I claim as new, and desire to secure by Letters Patent, is—

1. In a frost-proof device of the character described, a casing, a water-tank within the casing composed of a plurality of separable members, and locking members to hold the parts of the tank together disposed between, and forcibly bearing against, the casing and the water-tank.

2. In a frost-proof device of the character described, a casing, a water-tank within said casing composed of a plurality of separable members, and clamping members to hold the members of the tank against separation, comprising removable locking devices disposed between and forcibly bearing against the casing and the water-tank.

3. In a frost-proof device of the character described, a casing, a water-tank within said casing composed of a plurality of separable members, and locking-keys to clamp the members of the tank against separation, disposed between and forcibly bearing against the casing and the water-tank.

4. In a frost-proof device of the character described, a casing, a water-tank within said casing composed of a plurality of separable members, and sets of locking-keys to clamp the members of the tank against separation, disposed between and forcibly bearing against the casing and the tank, each said set comprising two straight keys and one tapering key.

5. In a frost-proof device of the character described, a casing, a water-tank within said casing composed of a plurality of separable members, and sets of locking-keys to clamp the members of the tank against separation, disposed between, and forcibly bearing against, the casing and the tank, each said set comprising two keys headed or hooked at their ends and one tapering key.

6. In a frost-proof device of the character described, a casing provided with perforations, a water-tank within said casing composed of a plurality of separable members, and clamping means to hold the members of the tank against separation, said means passing through the

perforations in the casing and between, and forcibly bearing against, the casing and the tank.

7. In a frost-proof device of the character described, a casing provided with perforations, a water-tank within said casing composed of a plurality of separable members, sills suitably arranged in the casing and provided with mortises, and clamping means to hold the members of the tank against separation, said means passing through the perforations in the casing and the mortises in the sills, and between, and forcibly bearing against, the casing and the tank.

8. In a frost-proof device of the character described, a hoopless and nailless water-tank comprising a plurality of members suitably mortised, a casing inclosing the tank and provided with perforations, and clamping means to hold the members of the tank against separation, said means passing through the perforations in the casing and between, and forcibly bearing against, the casing and the tank.

9. In a frost-proof device of the character described, a hoopless and nailless water-tank comprising a plurality of members suitably mortised, a casing inclosing the tank and provided with perforations, and locking-keys to hold the members of the tank against separation, passing through the perforations in the casing and between, and forcibly bearing against, the casing and the tank.

10. In a frost-proof device of the character described, a hoopless and nailless water-tank comprising a plurality of members suitably mortised, a casing inclosing the tank and provided with perforations, and sets of locking-keys to hold the members of the tank against separation, passing through the perforations in the casing and between, and forcibly bearing against, the casing and the tank, each said set comprising two keys headed or hooked at both ends and one tapering key.

11. In a frost-proof device of the character described, a hoopless and nailless water-tank comprising a plurality of members suitably mortised, tenoned and grooved, a casing inclosing the tank and provided with perforations, sills suitably arranged in the casing and provided with mortises, and sets of locking-keys passing through the perforations in the casing, but exteriorly of the tank, and passing also through the mortises in the sills.

12. In a frost-proof device of the character described, a hoopless and nailless water-tank comprising a plurality of members suitably mortised, tenoned and grooved, a casing inclosing the tank and provided with perforations, sills suitably arranged in the lower portion of the casing and adapted to support the tank, sills suitably arranged in the upper portion of the casing and extending across the top of the tank, all of said sills being provided with mortises, and sets of locking-keys passing through the perforations in the cas-

ing, but exteriorly of the tank, and also passing through the mortises in the several sills.

13. In a frost-proof device of the character described, a hoopless and nailless water-tank comprising a plurality of members suitably mortised, tenoned and grooved, a casing inclosing the tank and provided with perforations, a false floor to said casing forming air spaces or chambers, partitions between the walls of the casing and the walls of the tank, forming additional air spaces or chambers, sills suitably arranged in the lower portion of the casing and adapted to support the tank, sills suitably arranged in the upper portion of the casing and extending across the top of the tank, all of said sills being provided with mortises, and sets of locking-keys passing through the perforations in the casing, but exteriorly of the tank, and also passing through the mortises in the several sills.

14. In a frost-proof device of the character described, a hoopless and nailless water-tank comprising a plurality of members suitably mortised, tenoned and grooved, a casing inclosing the tank and provided with perforations, a false floor to said casing forming air-chambers, partitions between the walls of the casing and the walls of the tank, forming additional air-chambers, sills suitably arranged in the lower portion of the casing and adapted to support the tank, sills suitably arranged in the upper portion of the casing and extending across the top of the tank, all of said sills being provided with mortises, and sets of locking-keys passing through the perforations in the casing, but exteriorly of the tank, and also passing through the mortises in the several sills, a cover bridging a portion of the top of the tank and comprising a plurality of members to constitute air-chambers, and a cover extending over the first-mentioned cover and entirely over the tank, said second cover being formed in two, hinged sections, one section thereof comprising a plurality of members constituting air-chambers.

also passing through the mortises in the several sills, each said set comprising two similarly-shaped keys provided at both of their ends with heads or hooks, and one tapering, wedge-shaped key.

15. In a frost-proof device of the character described, a hoopless and nailless water-tank, comprising a plurality of members suitably mortised, tenoned and grooved, a casing inclosing the tank and provided with perforations, a false floor to said casing forming air-chambers, partitions between the walls of the casing and the walls of the tank, forming additional air-chambers, sills suitably arranged in the lower portion of the casing and adapted to support the tank, sills suitably arranged in the upper portion of the casing and extending across the top of the tank, all of said sills being provided with mortises, sets of locking-keys passing through the perforations in the casing, but exteriorly of the tank, and also passing through the mortises in the several sills, a cover bridging a portion of the top of the tank and comprising a plurality of members to constitute air-chambers, and a cover extending over the first-mentioned cover and entirely over the tank, said second cover being formed in two, hinged sections, one section thereof comprising a plurality of members constituting air-chambers.

In testimony whereof I affix my signature in the presence of two subscribing witnesses.

FRANCIS MARION VANDERGRIFT.
